B. BROIDO,
SUPERHEATER HEADER,
APPLICATION FILED NOV. 25, 1918.

1,328,364.

Patented Jan. 20, 1920.

BENJAMIN BROIDO. Inventor

By HIS Attorney O.V. Thiele

UNITED STATES PATENT OFFICE.

BENJAMIN BROIDO, OF NEW YORK, N. Y., ASSIGNEE TO LOCOMOTIVE SUPERHEATER COMPANY, OF NEW YORK, N. Y., A CORPORATION OF DELAWARE.

SUPERHEATER-HEADER.

1,328,364.

Specification of Letters Patent. Patented Jan. 20, 1920.

Application filed November 25, 1918. Serial No. 264,058.

To all whom it may concern:

Be it known that I, BENJAMIN BROIDO, citizen of Russia, and resident of New York city, in the county of New York and State 5 of New York, have invented certain new and useful Improvements in Superheater-Headers, of which the following is a specification.

The present invention relates in general 10 to superheaters and more particularly to the means used for securing the elements or units of the superheater to the headers.

If these units are rolled or expanded into the headers, their removal and re-attachment 15 is combined with great practical difficulty, and is at times quite impossible. For this reason a clamping means along the general lines of that hereinafter referred to has met with general favor, as it permits of 20 ready removal of any unit without injury to it or the header, and of equally ready re-attachment. Where the headers are made up of ordinary steel piping of usual thickness, some minor difficulties arise in the use 25 of such clamps, and it is the object of this invention to remove them.

The invention will be readily understood from the following description which is to be read in connection with the accompanying drawing. In the latter, Figure 1 represents, in cross-section, the two headers of a superheater with the ends of an element attached in the ordinary way with a clamp: Fig. 2 is a similar view illustrating my improvement, the section being taken on line 2-2 of Fig. 3. Fig. 3 is a bottom view of Fig. 2, all but one of the clamps having been removed and a portion being shown in section on line 3-3 of Fig. 2: Fig. 4 represents a 30 modification in a view similar to Fig. 3; Figs. 5, 6, 7 and 8 show other modifications in views like that of Fig. 2: Fig. 9 shows another modification in side elevation, a part of it being in section: and Fig. 10 35 shows in section another variation. Figs. 9 and 10 are on a slightly reduced scale. Throughout the drawing portions have been broken away, without, it is hoped, impairing the clearness of the figures.

As is well-known to those familiar with this art, the most ordinary form given to superheaters is that of a set of pipes, coiled or looped in some desired form, with the two ends of each secured to two headers, or 55 to two chambers of a single header. The

form, number, etc. of the pipes, or elements, is of no particular interest in the present connection, as the invention is concerned exclusively with the means of securing their ends to the headers. All that is shown, 60 therefore, of the elements are the ends, this being sufficient to illustrate the invention.

In Fig. 1 the two headers are given the reference numerals 1 and 1^a, while 6-6 are two of the element ends. The headers will 65 be noted to be circular in cross-section. If, as is usually the case, they are made of pipes of usual gage, it is ordinarily advisable to weld some material in the form of strips 2-2 to them to give some stock for forming 70 seats against which the pipe ends may bear. The form given in the illustration to the element end is what is known as the ball joint; and I use this throughout, by way of illustration, as I believe it is the best joint 75 yet proposed, without however wanting to be understood as limiting my invention in any way in this respect.

The ball end 5 (see right half of Fig. 1) is seated against the conical seat 4 in the 80 strip 2, so that the pipe end communicates with the interior of the header by way of the opening 5 extending through strip 2 and the wall of the header. It is held on its seat by clamp 7, a washer 8 being interposed. 85 The clamp 7 bears similarly at its other end against the lower side of the ball end of the other element end, holding it to its seat. A bolt 9 extends through a hole in the middle of clamp 7 its head bearing against the 90 under side of the clamp, and its upper end extending through a hole in bar 10, and carrying the nut 11 and the lock-nut 12. The bar 10 rests with its extremities on the headers 1 and 1^a. Evidently the ball ends 95 can be firmly held to their seats by a proper tightening up of nut 11.

There is nothing new in what has thus far been described. The purpose of referring to it to the extent I have is to point out the 100 defects my invention cures.

These defects are the following:

The distance between the element ends 6 is determined by the size of the pipe used for the headers, and with larger sizes this 105 distance, and the consequent length of the clamp 7 and bar 10 become inordinately great, and to give them sufficient strength and stiffness they must be made very heavy. The length of the bolt 9 is likewise depend- 110

ent on the size of the header, and as the amount of elongation due to its tension, and the variation in its length due to temperature variations are directly proportional to its length, it is very desirable to keep it as short as possible. When in this structure one clamp is drawn up tighter, there will always be a tendency for the adjacent ones on its two sides to become loosened due to a deformation of the header under the resulting pressure. This deformation is objectionable for other reasons too. Moreover, the pressure exerted by the clamps is such that pipe of ordinary gage cannot be used at all, as it proves impossible to get the connections tight.

All these objections are overcome and the use of pipe of ordinary gage becomes possible, by my invention. I weld a bar 13 (see Figs. 2 and 3) to each of the headers 1 and 1^a in the relation shown. Each bar 13 may extend from end to end of the header; or, as shown in Fig. 3, the bar need not be continuous, but may be in sections 13, 13^a, etc. These sections may be of any desired length, the advantage in using sections rather than a continuous bar being that temperature differences between the header and the attached bar will have less pronounced effects.

The bars 13 have extending into them from one side the holes 3^b which meet the holes 3^a, the latter extending through the wall of each header and into the bar. These channels, made up of the portions 3^a and 3^b, are equi-distantly spaced, and are so arranged that when the headers are in their final position, those of one bar and header lie opposite corresponding ones in the other.

The ends 6 of the elements are secured to the outer ends of the holes 3^b by means similar to those described for the corresponding function in connection with Fig. 1. The clamp 7 is, however, considerably shorter, and the bolt 9 is likewise shorter. The nut 11 bears on the bar 14 which rests in the two angular recesses 14^a, 14^b in the upper inner edges of the bars 13. This bar, it will be noted, serves not only as a bearing surface for nut 11, but also as a distance piece to keep the upper edges of the bars 13 properly spaced. The lower sides of the bars cannot approach toward or separate from each other, as they are engaged by the element ends.

It will be seen that the invention realizes the advantages above pointed out.

Fig. 4 illustrates a variation in the bar to which the ends are secured. Instead of two bars 13, a single one 13^a is used. The bolts 9 in this case will extend through the holes 15 instead of through the slot left between the two bars 13, 13 of Fig. 2. The channels 3^a—3^b, and the general means of attachment are the same as in the first case, only the

bar 14 may of course be omitted. This form has the advantage of greater rigidity.

Instead of placing the bars 13 in line with the two pipes 1 and 1^a, they may be arranged as in Fig. 5. The channels connecting the interior of each header with the lower surface of its bar is here also made up of two parts 3^a and 3^b, which however meet at an obtuse angle. The essential point of the structure is of course that the clamp 7 and bar 14 do not bear on any part of the pipes 1 and 1^a but only on the bars 13.

Figs. 6 and 7 illustrate the fact that the bars 13 need not be welded to the headers 1 and 1^a, but may be secured to them by means of short nipples 16 rolled or expanded into the holes 3^a and the corresponding openings in the headers. Except for this variation Fig. 6 will be seen to correspond to Fig. 2, and Fig. 7 to Fig. 5.

In all the forms thus far described the clamp 7 engages two element ends attached to the opposite bars 13. In Fig. 9 is illustrated a form in which the two ends engaged by the clamp 7 are secured to the same bar. This figure is a fragmentary view of one of the headers and its attached bar 13, looking directly at the bar, which is partly in section. The bolt 9 in this case extends through a hole in bar 13 between the two channels 3^b. By this construction the two headers do not become tied to each other except by means of the superheater elements.

A variation by which elements are secured to both sides of the bars 13, is shown in Fig. 8. The channel 3^a has leading out from it the two channels 3^b and 3^c to opposite faces of bar 13; and to the outer ends of 3^b and 3^c are held the ends of elements 6 and 6^a by means of the two clamps 7 and 7^a.

The variation of Fig. 10 illustrates a header with a plurality of channels 3^b all communicating with the same channel 3^a. It will be understood that a pipe end is attached to the outer end of each channel 3^b, the clamps being preferably arranged as in Fig. 9, i. e., parallel to the header. There is of course a plurality of such channels 3^b, and a second header corresponding to the one shown. While I have shown three channels 3^b, there may of course be but two, or there may be more than three.

It will be manifest that, while I have illustrated a few variations which may be given to my invention, many others will readily be resorted to in practising it as conditions or predilections may dictate and yet the spirit of my invention not be departed from. Thus, while I have shown the joint between the element end and the bar to be the familiar ball joint, it might be some other form, e. g. a gasket joint; the headers need not necessarily be cylindrical, but might be of some other shape, and they might be cast or

produced in any other desired way; the details of the clamp and bolt may evidently be considerably varied; each clamp may be modified and made to hold only one element end to a bar; the elements need not all be attached to the same side of the bars, as in Figs. 2 to 7 and in Fig. 9, but alternate ones may be secured to the opposite side. The following claims are intended to include 10 these and similar variations.

What I claim is:

1. In apparatus of the class described, the combination of a header having a plurality of openings through its wall; pipe ends corresponding in number to the openings; a bar parallel and adjacent to the header and with a like number of correspondingly spaced holes extending between two of its faces, said bar being secured to the header 15 so that the holes in one of the faces communicate with the openings through the header wall; and clamping means holding a pipe end against each hole in the second face of the bar, said clamping means engaging the pipes and the bar.

2. In apparatus of the class described, the combination of two headers, each provided with a plurality of openings through its wall; pipe ends corresponding in number to these openings; two bars parallel and adjacent to the two headers respectively and each with holes extending between two of its faces, the number and arrangement of the holes in each bar corresponding to the openings in one of the headers; said bars being secured to the headers so that the holes in one of the faces each communicate with a hole through a header wall; and clamping means holding a pipe end against each hole 40 in the second faces of the bar, said clamping means engaging the pipes in pairs and engaging both bars.

3. In apparatus of the class described, the combination of two cylindrical headers each provided with a plurality of openings arranged in a line parallel to the axis of the header; two prismatic bars parallel and adjacent to the two headers respectively and with holes through each extending between 45 two faces and corresponding in number and arrangement to the openings in the headers, said bars being secured to the headers so that one end of each hole registers with an opening in a header; the headers with their 50 attached bars being placed in parallel spaced relation, those faces of the bars, in which

are the other ends of the holes, lying in the same plane; and clamping means engaging the pipe ends in pairs and holding them against the last named ends of the holes, said clamping means also engaging the bars at points opposite the last named faces.

4. In apparatus of the class described, the combination of a header having a plurality of openings through its wall; a bar parallel and adjacent to the header and provided with a like number of correspondingly spaced holes extending into it from one of its faces there being other openings extending from a second of its faces to said holes; said bar being secured to the header so that the holes in its first named face communicate with the header wall openings; pipe ends; and clamping means holding a pipe end 70 against each hole in the second face of the bar, said clamping means engaging the pipes and the bar.

5. In apparatus of the class described, the combination of a cylindrical header, having through its wall a plurality of openings aligned parallel to the axis of the header; a prismatic bar with a like number of holes extending through it between two of its faces, the ends of the holes in one face being arranged to correspond to the header openings; the bar being secured to the header so the said ends of the holes through the bar communicate with the header openings; pipe ends corresponding in number to the holes through the bar; and clamping means holding a pipe end against each hole end in the second face of the bar, said clamping means engaging only the pipe ends and the bar but not the header.

6. In apparatus of the class described, the combination of two parallel headers, 1 and 1^a; a bar 13 secured to each, there being holes 3^a extending through the header wall and into the bar, and other holes 3^b extending inward from another face of bars 13 to meet the holes 3^a; pipe-ends 6; and clamping means engaging pipe-ends 6 and the bars 13, holding the former against the holes 3^b.

Signed at New York, in the county of New York and State of New York, this 16th day of November, A. D., 1918.

BENJAMIN BROIDO.
